CLAIM

The ornamental design for a device for producing non-hydrated purified hydrogen peroxide gas, as shown and described.

DESCRIPTION

FIG. 1 is a perspective view of a device for producing non-hydrated purified hydrogen peroxide gas.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a bottom plan view thereof; and,

FIG. 7 is a top plan view thereof.

The broken-line disclosure in the views is for illustrative purposes only and forms no part of the claimed design.
